SPRAYER FOR INSECTICIDES, DEODOR- ANTS, OR THE LIKE

Frank A. Ziherl, Euclid, Ohio, assignor to Z & W
Machine Products, Inc., Cleveland, Ohio, a cor-
poration of Ohio

Application November 6, 1952, Serial No. 22,174

Term of patent 14 years

(Cl. D31—3)

To all whom it may concern:

Be it known that I, Frank A. Ziherl, a citizen of the United States, residing at 22651 Edgecliff Blvd., Euclid, county of Cuyahoga and State of Ohio, have invented a new, original, and ornamental Design for a Sprayer for Insecticides, Deodorants, or the like, of which the following is a specification, reference being had to the accompanying drawings, forming a part hereof.

Fig. 1 is a top plan view of a sprayer for insecticides, deodorants, or the like, showing my new design;

Fig. 2 is a side elevational view of the sprayer;

Fig. 3 is a rear elevational view of the sprayer, and

Fig. 4 is a front elevational view of the sprayer.

The cord is omitted from Fig. 3 and is shown broken away in Figs. 1 and 4 for convenience of illustration.

I claim:

The ornamental design for a sprayer for insecticides, deodorants or the like, substantially as shown.

FRANK A. ZIHERL.
